UNITED STATES PATENT OFFICE.

CHARLES C. MEEKER, OF NEWARK, NEW JERSEY, ASSIGNOR TO BLISS & DRAKE, OF NEWARK, NEW JERSEY, A CORPORATION OF NEW JERSEY.

SAD-IRON.

1,263,916.

Specification of Letters Patent. Patented Apr. 23, 1918.

Application filed June 2, 1917. Serial No. 172,351.

To all whom it may concern:

Be it known that I, CHARLES C. MEEKER, a citizen of the United States, and a resident of Newark, in the county of Essex and 5 State of New Jersey, have invented certain new and useful Improvements in Sad-Irons, of which the following is a specification.

The invention relates to improvements in gas sad-irons, and it consists in the novel 10 features, structure and combinations of parts hereinafter described, and particularly pointed out in the claims. The object of the invention is to provide a gas sad-iron of novel and improved construction and 15 capable of successful use. Among the more important objects of the invention are to provide for adequate combustion within the body of the iron, the correct heating of the lower part of the iron so that the ironing 20 surface may be maintained at a proper temperature, efficient means for supplying an adequate volume of air for maintaining proper combustion at the burner within the chamber of the iron, and improved means 25 for securing the burner within the iron and the proper connection of the burner with the supply pipe leading thereto and connected with the iron, and also to provide a hinged cover for the iron adapted to receive 30 the handle and of such special construction that said cover may be easily manufactured and also contain an adequate air chamber serving to retard radiation of heat to the hand of the person operating the iron. 35 The iron of my invention comprises a hollow body portion, a novel hinged cover thereon carrying the handle, an elongated burner extending lengthwise within the hollow body portion of the iron, means for sup- 40 plying a regulated quantity of gas to said burner, and longitudinal and transverse air conduits for supplying air to the interior of the iron below the burner, whose outlet orifices are at the lower side thereof, one of 45 said conduits extending longitudinally from the rear end of the iron forwardly to the front end thereof through the bottom of the iron, and the other or transverse conduits leading from the sides of the iron 50 through the bottom thereof to said longitudinal conduit, and openings being provided in the top of said longitudinal conduit through which the air may ascend to the burner. 55 The invention will be fully understood

from the detailed description hereinafter presented, reference being had to the accompanying drawings, in which:

Figure 1 is a central vertical longitudinal section through a gas sad-iron constructed 60 in accordance with and embodying the invention, the section being on the dotted line 1-1 of Fig. 2;

Fig. 2 is a top view of the same;

Fig. 3 is a rear end view of the same; 65

Fig. 4 is a horizontal section through the body of the iron and is presented to illustrate the arrangement of the air conduits extending longitudinally and transversely in the bottom of the iron; 70

Fig. 5 is a vertical transverse section, partly broken away through the same, taken on the dotted line 5-5 of Fig. 4, and

Fig. 6 is a vertical transverse section 75 through the burner, taken on the dotted line 6-6 of Fig. 1.

In the drawings, 10 designates the body of the iron, 11 the cover thereon, 12 the handle connected with said cover, 13 the gas supply pipe connected with the body 10, 80 and 14 an elongated burner applied within the hollow interior of the body 10 and resting at its rear end upon an integral raised portion 15 at the bottom of said body and at its front end upon a raised portion 16 85 of said body, the front end of said burner 14 preferably being pointed and entering a correspondingly shaped recess 17 in the front inner wall of the body 10 above the seat 16 for the front end or portion of the 90 burner. The body 10 may be of any convenient outline and in the form shown has a pointed forward end and sides diverging therefrom on curved lines to the rear end of said body which is reasonably broad, as 95 shown. The body 10 has a hollow interior and is cast with an open upper end, and the sides of the body 10 are formed in their upper portions with elongated openings 18, while the rear end of said body is formed 100 in its upper edge with openings or recesses 19. The rear end of the body 10 is also formed with an opening 20 to receive the lower end of the gas supply pipe 13 which is threaded and engages a thread in the 105 walls of said opening 20. The lower end of the gas supply pipe 13 is screwed into the opening 20 and bears tightly against the rear end of the burner 14, and finally the pipe 13 is clamped in position by means of 110

a nut 21 which is on the threaded end of said pipe and may be screwed up against the rear end of the iron. The lower or forward end of the pipe 13 is beveled and engages a beveled seat in the end of the burner 14, and when screwed against the burner 14 binds the same in fixed position and creates a gas tight joint, as shown in Fig. 1.

The cover 11 fits over the upper end of 10 the body 10, and at its forward end is formed with ears 22 which straddle a lug 23 extending upwardly from the said body, and said cover is hinged to said body by means of a pin extending transversely through said 15 ears and lug. The rear end of the cover is provided with a spring latch 24 of known construction having a thumb piece 25 and a dog 26, the latter being adapted to enter an opening 27 in the rear end of the body 10 20 and detachably lock the rear end of the cover 11 upon said body. The cover 11 is formed with a top plate 28 and a bottom or supplemental plate 29, and these two plates are secured together by rivets 30 which are also 25 utilized to secure the frame 31 for the handle 12 to said cover. The plate 28 is recessed at its lower side, as at 32, this recess extending nearly the entire length and width of the bottom of the plate 28 and being bordered by an encompassing flange 33. The bottom plate 29 is spaced from the plate 28 at each side of the iron by a series of upwardly extending projections 34 which engage the flange 33 at opposite sides of the 30 cover and leave between them passages 35 for the entrance of air to the chamber formed between the plates 28, 29, this chamber being commodious by reason of the recessing of the bottom of the plate 28. The 35 plates 28, 29 are formed with hubs, as shown in Fig. 1, to receive the rivets 30 and space the frame 31 from the cover and aid in spacing the plates 28, 29 apart, said hubs also making it convenient to apply the rivets 40 45 30 through the frame 31, plate 28 and plate 29. The chamber between the plates 28, 29 of the cover by being freely open to the air retards the radiation of heat to the hand of the user of the iron.

50 The burner 14 is a hollow elongated casting extending from the rear to the front end of the body of the iron and provided at opposite side edges of its lower portion with burner orifices 36 for the gas. The burner 55 14 is hollow, as shown in Fig. 6, and preferably lined with wire gauze 37 which covers over the inner ends of the orifices 36. The burner 14 has at its rear end a broad foot 38 which rests flat upon the rear end of the 60 raised portion 15 of the bottom of the iron, as shown in Fig. 1, and at its front end said burner is pointed and enters the recess 17, as aforesaid, which centers the front end of the burner upon the support 16. The broad 65 flat foot 38 not only supports the rear end

of the burner 14, but prevents the burner during the screwing of the pipe 13 against it, from having any rotary movement.

The bottom of the iron on its upper surface is formed with a longitudinal raised portion 15 whose rear end is broadened, as shown in Fig. 4, and receives the foot 38 of the burner 14. The raised portion 15 is hollow and in communication with an opening 39 formed in the rear end of the iron and also with transverse conduits 40 through which air may pass to the chamber formed within said portion 15. Air also enters the chamber of said portion 15 through the opening 39, and said raised portion 15 of the bottom of the iron is formed in its upper surface with a series of apertures 41 out through which the air may pass for supporting combustion at the burner orifices 36, the burner 14 being longitudinally over said portion 15. The conduits 40 are formed in the bottom of the body of the iron, as shown in Fig. 5, and preferably these conduits will be arranged in staggered order, as indicated by the dotted lines in Fig. 4.

90 The gas pipe 13 with its nipple to receive a flexible gas-tube and having air inlets near its upper end, is of known type, with the exception that in this instance the lower end of said tube is threaded into the back of the iron and acts to force the burner 14 against the front end of the iron, this pressure not only serving to locate the burner 14 in permanent position, but also permitting such engagement of the lower end of the pipe 13 with the burner as to create a gas tight joint 95

100 The construction and arrangement of the conduits 40 and the elongated air chamber 42 within the bottom of the iron and the raised portion 15 thereof, have been found to be very efficient in properly supplying air to support combustion. The opening 39 at the rear end of the chamber 42 has outwardly diverging side walls so that the outer 110 end of the opening at the outer surface of the iron is commodious, as indicated in Figs. 3 and 4. The openings 41 in the raised portion 15 are in near relation to the bottom of the burner 14, and hence deliver the air 115 close to and between the two rows of flames which, when the iron is in use, are at the orifices 36.

120 My invention resides more particularly in the construction of the bottom of the iron and the mounting of the burner 14 thereover, and in the construction of the cover 11. The iron as a whole has been designed with the view of securing maximum efficiency, of enabling the maintenance of a proper and uniform heat at the bottom of the iron, of obviating any danger of the flames within the iron reaching the clothing of the operator or the goods being ironed, of preventing undue heating of the cover of the iron and 125 130

of providing a construction of durable character and capable of being readily manufactured and sold at reasonable expense.

What I claim as my invention and desire 5 to secure by Letters-Patent, is:

1. A gas sad-iron comprising a hollow body portion having a cover and handle, an elongated gas burner longitudinally disposed within said body portion over the bottom 10 thereof and having outlet orifices at its lower opposite edges, conduits in the bottom of the iron for admitting air to and through the central portion thereof below said burner, and means for supplying gas to the burner 15 and securing the burner in position, comprising a pipe threaded in a hole in the rear end of the iron and screwed against the rear end of the burner, and a nut on said pipe to bind against the rear end of the iron.
2. A gas sad-iron comprising a hollow body portion having a cover and handle, an elongated gas burner longitudinally disposed within said body portion over the bottom thereof and having outlet orifices at its 20 lower opposite edges, conduits in the bottom of the iron for admitting air to and through the central portion thereof below said burner, and means for supplying gas to the burner and securing the burner in position, comprising a pipe threaded in a hole in the rear end of the iron and screwed against the rear end of the burner, and a nut on said pipe to bind against the rear end of the iron, the 25 outlet end of said pipe being beveled and the rear end of said burner being correspondingly beveled to form a seat for the pipe and permit the creation of a gas tight joint.
3. A gas sad-iron comprising a hollow body portion having a cover and handle, an elongated gas burner longitudinally disposed 30 within said body portion over the bottom thereof and having outlet orifices at its lower opposite edges and a foot at its rear end to rest upon a portion of the iron and a 35 projection on its front end to enter a recess in the inner front wall of the iron, conduits in the bottom of the iron for admitting air to and through the central portion thereof below said burner, and means for supplying 40 gas to the burner and securing the burner in position, comprising a pipe entering the rear end of the iron and engaging the rear end of the burner for binding said burner against the forward portion of the iron.
4. A gas sad-iron comprising a hollow body portion having a cover and handle, a hollow elongated gas burner longitudinally disposed 45 within said body portion over the bottom thereof and having at its lower portion a series of outlet orifices for gas, an air conduit leading from the outside of the rear end of the iron longitudinally through the bottom of the iron and having discharge 50 openings in its top, and air conduits leading laterally through the bottom of the iron to said longitudinal conduit, the bottom of the iron having a longitudinal raised portion on its upper surface to aid in affording space for said longitudinal conduit and which 55 portion is broadened at its rear end, and said burner having a foot to rest upon said broadened end of said raised portion.
5. A gas sad-iron comprising a hollow body portion having a cover and handle, an elongated gas burner longitudinally disposed 60 within said body portion over the bottom thereof and having outlet orifices at its lower opposite edges and a foot at its rear end to rest upon a portion of the iron and a 65 projection on its front end to enter a recess in the inner front wall of the iron, conduits in the bottom of the iron for admitting air to and through the central portion thereof below said burner, and means for supplying 70 gas to the burner and securing the burner in position, comprising a pipe entering the rear end of the iron and engaging the rear end of the burner for binding said burner against the forward portion of the iron.

Signed at Newark, in the county of Essex, and State of New Jersey, this 18th day of April, A. D. 1917.

CHARLES C. MEEKER.

Copies of this patent may be obtained for five cents each, by addressing the "Commissioner of Patents, Washington, D. C."

It is hereby certified that the assignee in Letters Patent No. 1,263,916, granted April 23, 1918, upon the application of Charles C. Meeker, of Newark, New Jersey, for an improvement in "Sad-Irons," was erroneously described and specified as "Bliss & Drake," whereas said assignee should have been described and specified as *Bliss & Drake*; and that the said Letters Patent should be read with this correction therein that the same may conform to the record of the case in the Patent Office.

Signed and sealed this 14th day of May, A. D., 1918.

[SEAL.]

R. F. WHITEHEAD,

Acting Commissioner of Patents.
